[57] CLAIM

The ornamental design for a front access stacking bin, as
shown and described.

DESCRIPTION

FIG. 1 is a perspective view of a front access stacking
bin showing my new design;

FIG. 2 is a right side elevational view thereof; the left
side elevational being a mirror image thereof;

FIG. 3 is a top plan view thereof;

FIG. 4 is a front elevational view thereof;

FIG. 5 is a bottom plan view thereof;

FIG. 6 is a rear elevational view thereof;

FIG. 7 is a perspective view of an alternate embodiment
of FIG. 1; and,

FIG. 8 is a top plan view of FIG. 7.

The corresponding views of an alternative embodiment
in FIG. 7 are similar to as shown in FIG. 2 and 4
through 6 respectively.

FIG. 1

FIG. 2

FIG. 3

FIG. 4

FIG. 5

FIG. 6

FIG. 7

FIG. 8
